ARMORED FLOOR STRUCTURE

John M. Keown, Chicago, Ill., assignor of part
interests to Arthur E. Sangdahl, W. Forrest
Ogle, Edwin J. Learned, and Bentley F. Rams-
dell

Application June 23, 1932, Serial No. 618,923

12 Claims. (Cl. 94—8)

This invention relates to floor structures, particularly to a construction for providing a wear resistant surfacing for floors, stair treads, and the like.

5 A general object of the invention is the provision of a structure of composite character, comprising metallic elements combined with floor surfacing material, which will possess desirable wear-resisting qualities and afford a tread surface 10 having desirable frictional characteristics designed to prevent slipping.

Another object is the provision of such a construction in which the dissimilar component materials are combined and bonded together in a 15 manner effective to hold them securely in a unitary structure.

Yet another object is the provision of a structure of the sort above specified in which the dissimilar component materials are securely 20 bonded in a unitary structure, yet a limited displacement of portions of one with respect to the other is accommodated within the structure.

Yet another object is the provision of a floor surfacing structure made up of metallic and non- 25 metallic elements combined in such fashion as to form unitary sections and to provide for the effective interlocking of the sections to one another.

Other and further objects will be pointed out or indicated hereinafter or will be apparent to 30 one skilled in the art upon an understanding of the invention or its employment in use.

For the purpose of aiding in explanation of the invention, I show in the accompanying drawings forming a part of this specification, and herein- 35 after describe, certain structural embodiments of the invention, but it is to be understood that these are presented for purpose of illustration merely and are not to be construed in any fashion calculated to limit the appended claims short of the 40 true and most comprehensive scope of the invention in the art.

In said drawings,

Fig. 1 represents top marginal views of two formed strips or bars suitable for use in the 45 structure;

Fig. 2 is a side elevational view of one of said bars;

Fig. 3 is a top or plan view illustrating a section of a floor structure embodying the invention, said view showing part of the structure in completed condition and part in uncompleted condition and part in cross section;

Fig. 4 is a fragmentary sectional view of a portion of grating constituting part of the invention;

Fig. 5 is a perspective view of a completed section of a floor structure embodying the invention;

Fig. 6 is a perspective view of a portion of a similar section, showing the side opposite that shown in the side margin;

Fig. 7 is a top view of a floor structure comprising a plurality of conjoined sections; and

Fig. 8 is a detail showing a section along a joint, approximately on line 8—8 of Fig. 7.

It is desirable that floor surfaces have certain 65 frictional characteristics which will afford secure footholds and prevent slipping of people who walk upon them. It is also desirable that they possess effective wear resistant qualities. It is sometimes desirable that they have certain 70 yieldable qualities, for the purpose of making them comfortable under foot. It is particularly desirable that they hold to shape and be proof against warping, separation and disintegration. It is also desirable that they be qualified to support 75 substantial weight without permanent deformation. Few, if any, materials suitable for floor surfacing possess in themselves all of these desirable characteristics. A metal, for example, may possess the desirable wear resistant 80 quality, yet with use, metal surfaces become smooth and slippery under foot. Various mastics have desirable frictional characteristics and yieldable quality, yet are not qualified to sustain 85 heavy weight or resist wear. The combination of different materials into a unitary floor surfacing structure of such character that it will afford the desired characteristics in use and yet retain structural integrity is a matter of considerable difficulty.

90 The present invention provides a floor surfacing structure made up of metallic components, in the nature of grating, and other components, in the nature of a body material, such as a mastic, concrete, or the like, so combined as to avail of the desired characteristics of the different materials and to maintain them securely united in the desired relationship and condition. The nature of the invention will be most quickly ascertained from a consideration 95 of particular examples illustrated in the drawings and now to be described.

100 Referring to the drawings, it will be seen that the structure, as represented in Fig. 3, comprises a metallic fabric in the nature of a grating or network, made up of a plurality of sinuously formed bars or strips 10, one of which is shown in side elevation in Fig. 2, and two of which are 105 shown in separate relationship in Fig. 1. The form of these bars provides oppositely directed 110

bights 11 and 12, regularly formed throughout the length of the bars, said bights having portions of appreciable length extending parallel to the longitudinal axis of the bar and lying in planes parallel to each other. For convenience of designation, I will refer to these portions of the bights as contact portions, and to the intermediate portions 14 as spacer portions. As seen in Fig. 2, the contact portions are provided with apertures 15 therethrough in their middle areas, said apertures terminating considerably short of the adjacent spacer portions 14, and the spacer portions are provided with apertures 16. In the fabrication of the grating, the bars are placed on edge in collateral relationship with the contact portions 11 of one bar in contact with the oppositely displaced contact portions 12 of the adjacent bar and with the apertures 15 of the juxtaposed contact portions in register, and the juxtaposed bars are permanently connected to each other by connections formed at opposite sides of the apertures. One manner in which such connections may be formed is by spot welding, and in the examples here presented spot weld connections are indicated at C. As a measure for facilitating the making of such spot weld connections, the bars may be formed initially with slight embossments B, as illustrated in Fig. 1, to afford current concentrating contact points between the juxtaposed bars. At the completion of the connections, however, the contact portions of adjacent bars are in close abutment, as shown in Fig. 3. By virtue of the connections of the bars thus formed, the contact portions of the juxtaposed bars are secured to each other in definitely fixed relationship at opposite sides of the apertures, so that the contact portions of one bar cannot be shifted or deflected in any direction relative to those of the adjacent bar. This is a feature of importance, as hereinafter pointed out. Uniting of the bars as above described provides a grating fabric affording interstices 17, here shown as of hexagonal form, said interstices being in communication with one another through the apertures 15 and 16.

A network or grating of the desired extent having thus been fabricated by the connection of a plurality of the bars arranged and connected as above described, a suitable body material or filling material is incorporated with the grating. This body material is applied in a plastic condition and in quantity such as to fill the interstices of the grating. It may be concrete or similar cementitious conglomerate, a mastic composition, rubber, or other plastic or moldable material having the desired characteristics. It is applied under sufficient pressure to insure its completely filling the interstices and portions of it occupying the apertures 15 and 16, whereby the portions of body material in different interstices are bonded to each other through the intervening bar portions. On the tread surface, the body material is levelled off flush with the margins of the bars.

In Fig. 3 is shown a section of the grating, part of same being filled with the body material, as indicated at 18, and part not yet filled, the portion at the lower right hand corner being shown in section to illustrate the bonding connections through the apertures 15 and 16. In Fig. 4 is shown a variant form of grating, which differs from that shown in Fig. 3 in the particular that the alternate bars are provided with the apertures 16, the intervening bars not having such aper-

tures, but all of the bars having apertures 15, and all being connected as above described.

When the body material is suitably solidified, it forms, in combination with the grating, a composite fabric of structural integrity in which the metallic members constitute the principal load-supporting and wear-resisting elements, and in combination with the body material afford the desired frictional quality in the tread surface. The connection of the abutting contact portions of the bars at longitudinally spaced points relative to the apertures 15 is of advantage particularly in a structure wherein the body material is of yieldable character, as it holds the connected bar portions 11 and 12 in fixed relationship and prevents the shearing off of the bonding portions of the body material occupying the apertures 15. For illustration, a heavy local loading of one of the bars, as on one of the spacer portions 14, would tend to displace it downwardly relative to the adjacent bars, and thus produce a shearing action between the connected portions 11 and 12 across the apertures 15. Such local loading of one of the bars likewise might tend to pull its contact portions away from those of the adjacent bars and exert tension upon bonding portions of the body material in the apertures 15. By fixedly connecting the abutting contact portions of adjacent bars at points spaced longitudinally relative to the apertures 15, such relative movement of the contact portions is definitely prevented, and the integrity of the bonds of the body material through the apertures 15 is accordingly safeguarded.

In addition to affording a bonding connection between the different areas of body material and between the body material and the bars, the provision of the apertures 15 and 16 accomplishes a further beneficial result in a structure wherein the body material remains in a more or less plastic or elastically deformable condition, by providing pressure-relieving channels for the portions of body material which are otherwise segregated and circumscribed by the bars. For illustration, if the portion of semi-plastic or elastically deformable body material within one of the interstices were subjected to a heavy loading, the pressure would tend to spread or displace it outwardly, and possibly displace some of it over the margins of the encompassing bars, where such displaced portions might be sheared off against the bars, as by the rolling of a heavy article of furniture over them. The provision of the apertures 15 and 16 at different sides of the segregated areas of body material affords relief channels accommodating the elastic displacement of some of the material from a heavily loaded area and thus decreases the likelihood of the material being crowded onto the upper margins of the bars. In instances where the body material is of rigid character, such as concrete, the provision of the apertures 16 at the various sides of the segregated areas affords bearings whereby pressures imposed upon the segregated area of body material are distributed to the several bar portions which encompass that area.

Floor structures of the construction above described may be constructed at the place of installation by providing the grating in conveniently sized sections, assembling the sections of grating in the desired location by disposing them in proper relationship on the floor slab or other floor structure of the building, and then filling the grating with the body material. The floor structure may also be made at the factory in complete sections having the grating and body mate-

rial permanently combined before the structure is taken to the place of installation, the individual completed sections then being assembled and combined with one another on the job to cover the desired floor area.

In Figs. 5 to 8 inclusive are illustrated features of the invention which have to do particularly with the interfitting of such separate grating sections or complete structure sections for the purpose of holding them in the desired relationship through mutual cooperation of the sections with one another. Fig. 5 illustrates a completed section of the structure in the form that it may be turned out at the factory, the grating and body material being permanently combined to form a unit of convenient size and form. It will be observed that at the ends of the sections the grating bars terminate at approximately the median line of the connected contact portions, so that the apertures 15 present notches which open at the ends of the section, and that at the ends the body material is formed out flush with the ends of the bars and is formed with a groove 20 aligning with said notches. It will also be observed that along the side margins of the section the body material is formed out flush with the outer faces of the contact members 11 and 12. Along one side of the section the apertures 15 of the contact members are left void, while along the opposite margin of the section, which is illustrated in Fig. 6, one of the apertures 15 is left void while the others are occupied by portions of the body material which extend therethrough and project as lugs 21. These lugs 21 are of such size as to fit in apertures 15 at the margin of a similar section.

Sections of this character may be made up conveniently by the use of a mold in which the section of grating is placed and filled with the body material, the mold being provided with suitable elements for forming the grooves 20 and lugs 21 and maintaining the desired apertures 15 void.

When a number of the sections so formed are assembled with one another, margin to margin, the lugs 21 of one section are fitted into void marginal apertures 15 of the juxtaposed section or sections, thus forming an interlock for maintaining the abutting margins of the sections in the same horizontal plane and maintaining the abutting sections against relative longitudinal movement. Such an assembly of sections is illustrated in Fig. 7, the sections in adjacent courses here being shown in broken joint relationship.

For connecting the sections which are abutted end to end, a key or spline 22 is provided, same being of such size as to fit closely in the end grooves 20 of the abutted sections, thus to hold them in the same plane. Such spline may be of sufficient length to extend across the ends of a plurality of sections, thus to key together collaterally abutted sections as well as the end-abutted sections. In the broken joint arrangement illustrated in Fig. 7, the keys are of such length as to extend at their ends beyond the sides of a section and seat in marginal apertures 15 of the sections which are in lateral abutment with it.

It will be observed that a plurality of sections may be thus assembled in such fashion as to preserve the continuity and regularity of the grating pattern and to inter-engage or interlock the sections in such fashion that they function mutually to hold one another in place and in the desired relationship.

What I claim is:

1. An armored floor structure comprising, in combination, a plurality of sinuously formed metallic bars arranged on edge in collateral relationship and having longitudinally spaced contact portions of juxtaposed bars in lateral abutment, said laterally abutting contact portions having apertures therethrough spaced from their upper and lower margins, and said abutting contact portions being rigidly fastened together on opposite sides of their apertures, the plurality of bars thus secured to one another forming a grating, and a filling of coherent body material filling the interstices of said grating and having portions which occupy adjacent interstices bonded together through said apertures. 80

2. An armored floor structure as specified in claim 1 and wherein the body material is of elastically deformable character. 85

3. An armored floor structure as specified in claim 1 and wherein the respective bars have spacer portions extending transversely of their longitudinal axes, said spacer portions being provided with apertures therethrough, and the body material has portions occupying said last mentioned apertures. 95

4. An armored floor structure as specified in claim 1 and wherein the abutting portions of juxtaposed bars are secured together by welds located adjacent opposite sides of the respective 105 apertures.

5. An armored floor structure comprising a sectional unit made up of a section of reticulated grating with a filling of body material filling the interstices thereof, the elements of said grating having apertures therethrough located between the upper and lower surfaces of the body material and the body material having portions occupying said apertures and bonding together the portions of body material in different interstices, said 115 grating having portions extending to the end and side margins of the section and provided with apertures open at said margins for accommodation of anchoring elements, the body material at the margins of said section being flush with the 120 outer surfaces of said grating portions.

6. An armored floor structure comprising a plurality of sectional units as specified in claim 5, said units having lugs extending from a margin thereof for fitting in marginal apertures of the 125 grating of other sections, for the purpose of interengaging one section with another at their margins.

7. An armored floor structure comprising a plurality of sectional units constructed as specified in claim 5 and adapted to be abutted marginally with their upper surfaces in the same plane, together with a key adapted to engage in the marginal grating apertures of abutted sections for the purpose described. 130

8. An armored floor structure comprising a plurality of sectional units as specified in claim 5 and wherein the upper margins of the grating elements form a regular pattern which is continuous from section to section when the sectional units are assembled in marginal abutment. 135

9. An armored floor structure as specified in claim 5 and wherein portions of the margins of the section are formed by portions of the grating and other portions of the same margins are 145 formed by portions of the body material.

10. An armored floor structure unit comprising a section of metallic grating formed of sinuously shaped bars rigidly connected to one another at intervals spaced longitudinally thereof, said bars 150

having apertures therethrough spaced from their upper and lower margins, a filling of body material filling the interstices of the grating flush with the upper and lower margins of the bars and bonded together through said apertures, said unit having straight margins formed in part by portions of the outer bars and in part by portions of body material occupying re-entrant sinuosities of said outer bars and held in place by said bonding.

11. An armored floor structure comprising a plurality of units constructed as specified in claim 10 and wherein the upper margins of the bars form a regular pattern, said units having means

for interengaging one with another at their margins with marginal bar portions of juxtaposed units in abutment.

12. Armored floor structure comprising a grating formed of sinuous strips arranged on edge with longitudinally spaced bights of juxtaposed bars rigidly secured together in lateral abutment, the bights being provided with apertures therethrough spaced from their upper and lower margins, and coherent body material filling the interstices of the grating and having portions thereof which are in adjacent interstices bonded together through said apertures.
